DESIGN FOR A COMBINED CONNECTING CLIP FOR MATCH AND CIGARETTE PACK- AGES

Frank M. Sprague, Boise, Idaho

Application March 10, 1939, Serial No. 83,493

Term of patent 14 years

To all whom it may concern:

Be it known that I, Frank M. Sprague, a citizen of the United States and a resident of the city of Boise, county of Ada, and State of Idaho, have invented a new, original, and ornamental Design for a Combined Connecting Clip for Match and Cigarette Packages, of which the following is a specification, reference being had to the accompanying drawing, forming part thereof.

bined connecting clip for match and cigarette packages illustrating my design; and

I claim:

The ornamental design for a combined connecting clip for match and cigarette packages, as shown.

FRANK M. SPRAGUE.
